UNITED STATES PATENT OFFICE.

JAMES M. BUTCHER, OF CHICAGO, ILLINOIS, ASSIGNOR TO HARRY N. ANDREASEN, OF CHICAGO, ILLINOIS.

SAVINGS BANK.

Application filed June 13, 1923. Serial No. 645,200.

To all whom it may concern:

Be it known that I, JAMES M. BUTCHER, a citizen of the United States, and a resident of Chicago, in the county of Cook and State of Illinois, have invented certain new and useful Improvements in Savings Banks, of which the following is a description, reference being had to the accompanying drawings, which form a part of my specification.

10 My invention relates to improvements in savings banks for small coins, such as dimes and the like, of the type adapted to be carried in the pocket of the user and firmly clipped or held in place in such manner

15 that the coins or dimes may be readily inserted into the bank without its removal from the pocket.

The invention has for its object the provision of a removable portion or end of the 20 coin holder upon the operation of locking mechanism by means of a suitable key in the possession of an authorized individual or the savings bank teller so that the removal of coins by an unauthorized individual, as well 25 as by the owner will be impossible.

A further object of my invention is to provide locking means of such nature on the bank interior, that manipulation of the lock by the proper party will at all times be possible even though the receptacle or bank is 30 entirely filled with coins; the construction being such that the coins within the receptacle or bank will be forced into such superposed position that the coins cannot interfere with the easy insertion of the key and its ready manipulation.

The various objects and advantages of my invention will be more readily apparent from the detail description of the drawings, 40 wherein:—

Figure 1 is a perspective view of the bank with a portion of the side wall broken away to disclose my improved locking mechanism.

Figure 2 is a longitudinal sectional view 45 thereof.

Figure 3 is an enlarged cross sectional view taken on the line 3—3 of Figure 2 looking in the direction of the arrows.

Figure 4 is an enlarged detail sectional 50 view taken substantially on the line 4—4 of Figure 2 looking in the direction of the arrows.

Figure 5 is an enlarged view in perspective of the removable end or cap with the 55 locking mechanism shown in Figure 1.

Figure 6 is a perspective view of a coin bank, with a portion of the side wall broken away, illustrating a modified form of the invention.

Figure 7 is a longitudinal sectional view 60 thereof.

Figure 8 is a perspective view of another modified form of the invention, with a portion of the lower end of the wall broken away to show the internal locking mechanism. 65

Figure 9 is a side elevation of the construction shown in Figure 8 with the lower portion thereof shown in section.

Figure 10 is a detail sectional view, taken 70 substantially on the line 10—10 of Figure 9, with a portion of the key inserted in place.

In the exemplification of the invention as disclosed in the first five figures of the drawings, the bank comprises a suitable elongated receptacle 15, of metal or any other suitable material and preferably elliptical in cross-section in order to permit the bank to be easily carried in the vest pocket or inside coat pocket of the user. The receptacle 75 15 is provided with a sloping bottom as at 16 to induce the coins or dimes, indicated at A, to be superposed in an inclining manner, which is also necessitated by the cross-sectional dimensions of the receptacle; that is to say the major axis of the cross sectional area of the receptacle is just sufficient to receive the coin or dime which is of larger diameter than the minor axis of the cross-sectional area. The receptacle or coin-holder is therefore provided with an inner sloping bottom 80 16, as shown, so that the flat faces of the coins may be flush with each other in the superposed position shown. The inclined outer surface or bottom also enables the receptacle or bank to be easily inserted or slid 85 into the vest-pocket of the user, where it is preferably clipped or secured in place by means of a suitable spring clip 17 secured to the upper end of the bank or receptacle; 90 namely to the removable top or cap 18 in the construction shown in the first five figures of the drawings.

The cap or top 18 is preferably adapted to overlap or fit onto the upper end of the receptacle 15; while at a suitable point removed from the perimeter of the cap it is provided with a depending flange portion 19 adapted to fit snugly into the upper end of the receptacle 15. 105

The flange 19 is of sufficient width to permit a portion thereof to be slit or partially cut as at 20, with one end severed as at 21, while the other end remains integral so as to provide a yielding tongue or spring detent 22. The flange with the tongue is of suitable resilient metal in order that the tongue 22 may be flexed or yieldingly moved out of normal position through the action 10 of a suitable key and at the same time spring back to normal and locking position when the top or cap 18 has been completely forced into place. The severed end of member 22 is shown provided with an aperture or 15 socket 23, intended to receive a small pin or boss 24 secured on the inner wall of the receptacle 15 at a point where it will register with the aperture 23 when the cap or top 18 has been completely inserted in place. 20 When the boss or pin 24 has entered the aperture or socket 23, it is evident that the upward removal of the cap or top 18 will be impossible.

The member 22, at a suitable point removed from the severed end and from the socket or aperture 23, is provided with a partially severed portion which is bent inwardly and preferably at right angles to provide a lip or small tongue 25 and provide 30 a key-receiving pocket. The lip 25 is adapted to be engaged by the base or bit 26 of a suitable key indicated at 27, which is intended to be inserted through the key-hole or opening 28 formed in the top or cap 18, 35 immediately above the socket or pocket formed by the partially severed bent portion or lip 25, as clearly shown in Figures 1 and 3. The lip 25 is formed so as to be disposed slightly to one side of the vertical 40 axis of the keyhole in order that the bit or foot 26 of the key 27 will be disposed between the side wall of the receptacle 15 and the lip 25. It is evident that turning of the key in proper direction will cause 45 the bit 26 thereof to engage with the lip portion 25 and cause the severed end of the tongue or detent 22 to be forced away from the side wall of the receptacle 15 and therefore out of holding relation with the boss 50 or pin 24. As soon as the tongue or member 22 has been moved inwardly beyond the boss or pin 24, it is evident that an upward pull 55 on the key and the cap 18 will cause the latter to be withdrawn and access to the receptacle interior to be had.

In order that the coins, especially after the receptacle has been completely filled, may not become displaced or so lodged as to interfere with the locking tongue or detent 22, or to interfere with the proper insertion of the key, the top or cap 18 is preferably provided with a transversely disposed partition or rib 29 intermediate of the key-receiving opening or hole 28 and the 65 coin-receiving slot or opening 30. The coin-

receiving slot extends transversely along the major axis of the cap or top as shown in Figure 1 and the top, at one side of the slot, preferably the side disposed toward the clip 17 and therefore what might be the 70 forward side relative to the position of the receptacle in the pocket, is shown slightly dished as at 31 in order to readily position the coin for insertion. By slightly dishing the top downwardly adjacent to the slot 75 as shown, it is apparent that the perimeter or rim of the coin when moved across the top of the receptacle will engage the opposite wall of the slot, namely the undished side toward the keyhole or opening and thus 80 position the coin for insertion without necessitating special care on the part of the user in locating the slot. In order that the flange 19 of the cap may pass over the boss or pin 24, I show the flange at a point immediately 85 beneath the socket 23 of the tongue 22, slightly dished or bent inwardly as shown at 19a.

The flange 19 of the top or cap is also shown provided with a yielding or spring strip 32, which may be of the construction shown in Figures 2 and 3, with the upper end preferably bowed and disposed slightly beneath the ends of the coin-receiving slot 30, as more clearly shown in Figure 3, so 90 as to seal the slot against the accidental removal of coins therethrough; the spring strip 32 being constructed to move toward the side of the coin-slot 30 and readily yield to slight pressure of the coin while being 95 inserted through the slot.

In Figures 6 and 7, I show a modification of my invention in so far as the locking means is concerned; the receptacle or coin-holding portion 15 being identical with that 105 shown in Figure 1. The cap or top 33 in the construction shown in Figures 6 and 7 is provided with a depending flange 34 adapted to snugly enter the coin-holding receptacle 15; while the top is provided with the 110 coin inserting slot 30 and slightly dished as at 31 similar to the construction shown in Figure 1. One side of the depending flange 34 is provided with a slot or socket 35 adapted to receive the slight shoulders 36 formed 115 on a spring strip or detent 37 which is secured on the interior of the receptacle at any suitable point as at 38. The spring strip or detent 37, adjacent to the point where it is provided with the small shoulders 120 or burrs 36, is bent inwardly and upwardly as shown at 39 in Figure 7; with the upper end thereof disposed intermediate of a guard or narrow strip 40 secured to the top or cap 33 and a depending wall or partition 125 41 also secured to the cap or top 33 at a point adjacent to the coin-receiving slot 30. The guard or strip 40, with the flange 34 of the cap 33, form a pocket for the shank of the key; while the strip 40 is formed to per- 130

mit the base or bit of the key to pass therebeneath and engage with the end 39 of detent 37 when the key is turned. The cap or top 33, at a point intermediate of the 5 main flange 34 and the guard strip 40, is provided with a key-receiving slot or opening 42, whose formation may vary to compel the use of differently shaped keys if desired. Upon inserting a proper key through slot 10 42, the lower end or bit thereof is caused to engage with the free upper end 39 of detent 37 and cause the latter to be flexed in a direction which will force the shoulders or burrs 36 out of the socket or slot 35 in flange 15 34 of the top or cap 33 and thus permit the latter to be withdrawn from the coin-holding receptacle 15.

The cap or top 33 is also shown provided with a yielding strip or guard member 43 20 which may be similar to the guard or member 32 in the previously described figures, with the ends of the guard 43 normally disposed slightly beneath the coin-receiving slot 30 so as to prevent the coins being withdrawn or passing through the introducing slot 30. The guard 43 may be secured to the main flange of the cap or top 33 in any suitable manner, as for example by the rivet shown at 44. The cap 33, like the cap 18, 30 is also preferably provided with a spring clip 17 whereby to firmly hold the receptacle in the pocket of the user.

In Figures 8 to 10, I show another modification of the invention, wherein the coin-receiving receptacle 45, in so far as its transverse dimensions are concerned is substantially similar to those previously shown and described; the receptacle in Figures 8 to 10, however, being provided with a permanently secured top or cap 46 provided with the coin-introducing slot 30 and also provided with a spring clip 17. In the receptacle shown in Figures 8 to 10, the bottom 47 of the receptacle is made removable. In this construction the removable lower end is provided with the flange portions or walls 48 adapted to extend into the receptacle and provided with an inner end wall 49, which is preferably arranged at an inclination as

40 shown so as to provide a sloping interior bottom whereby the coins will be caused to stack in the inclining superposed relation shown in dotted lines in Figure 2, thus permitting the receptacle to be made relatively 45 narrow so as to be conveniently carried in the pocket, to easily accommodate the coins and permit of a maximum number of coins to be placed in the receptacle or bank. The walls 48 and 49, with the bottom 47, in

50 reality constitute a pocket or housing for the locking mechanism which consists of a small pin or boss 50 formed or secured to the inner wall of the receptacle 45 and which is adapted to enter a slot formed in 55 the side wall 48 and the slot or socket 51

formed in a spring strip 52 secured at 53 to the bottom 47 and extending across the slot in the side wall 48. The spring strip 52 is also shown provided with the inwardly curved or bent lip 54 (which may consist of 70 the severed metal for producing the socket 51) at a point adjacent the upper end of the spring strip or detent which is intended to be engaged by a suitable key 55 intended to be inserted through a slot 56 formed in the 75 bottom of the lower end member 47. The key comprises a suitable blank, one end whereof is shown reduced and slotted as at 57, and said end slightly bent as shown at 58 so as to engage or hook over the lip 54 80 of spring strip or detent 52. With this formation of key, it is apparent that upon pulling the key outwardly, the spring strip 52 will be bent inwardly and therefore away from the pin or boss 50 secured to the wall of the receptacle, thereby permitting the bottom member 47 to be withdrawn and access to the bank had for the removal of the coins. In order that unlocking of the bottom member 47 by unauthorized individuals may be 90 prevented, it is shown provided with one or more upstanding and slightly curved or bent lugs or lips 59, which may be formed integral with the attached end of the spring strip or detent 52. These lugs or lips 59 are bent 95 in a direction to extend over the key-receiving slot 56. With this construction, it is evident that the key must be provided with a correlated surface in order to permit its insertion; for example the key 55, as shown in Figure 10, is provided with the additional slots 60, 60, disposed on opposite sides of the main slot 57, adapted to receive the lugs or lips 59 and which will permit proper 100 tilting of the key to engage the lip 54 of the 105 detent 52.

As is clearly apparent from the various constructions shown and described, the locking mechanisms will permit of various combinations which will enable the savings 110 banks to be employed by different banks or institutions, with the locking mechanism on the banks used by one institution differing from those of the other.

In all of the constructions shown in the drawings, it is apparent that the receptacles or banks may be filled to the maximum capacity without in any way interfering with the locking mechanism or its proper and easy manipulation.

The removable end in Figures 1 to 5 is shown provided with a strip or guard 61 arranged adjacent to the key slot 28 and above the bent portion or lip 25 of the tongue 22. The strip or guard 61 in the construction shown in Figures 1 to 5; the strip or guard 40 in the construction shown in Figures 6 and 7 and the lugs or lips 59 in the construction shown in Figures 8 to 10 all constitute wards, which may be va-

ried in construction so as to necessitate the use of keys having differently formed bits correlated to the wards; the various locking mechanisms disclosed permitting various combinations to be formed.

I have shown what I believe to be the simplest embodiment of my invention which has been described in terms employed merely as terms of description and not as terms of limitation, as structural modifications are possible and may be made without, however, departing from the spirit of my invention.

What I claim is:—

1. A coin savings bank, comprising an elongated receptacle, with the distance between the front and rear walls thereof being less than the diameter of the coin intended to be inserted therein, the receptacle being provided with an inner sloping bottom to hold the coins in superposed inclining relation, a coin-slot in one end, a guard yieldingly mounted beneath said slot, one end of the receptacle being removable, composite means carried by said removable end and the receptacle whereby the removable end is normally locked in place, and means whereby improper manipulation of said composite means is prevented.

2. A coin bank, comprising an elongated receptacle having an inner inclined bottom and a coin-slot in one end, one of the ends being removable and provided with a key-slot and a lock forming element, a yielding guard normally extending beneath the coin-slot, and a key controlling ward secured to said removable end adjacent to the key-slot.

3. A coin bank, comprising an elongated receptacle having an inner inclined bottom and a coin-slot in one end, one of the ends being removable and provided with a key-slot and a portion adapted to form locking engagement with the receptacle, a variable key controlling ward secured to said removable end adjacent to the key-slot, and means whereby removal of the coins through the coin-slot is prevented.

4. A coin bank, comprising an elongated receptacle having an inner inclined bottom and a coin-slot in one end, one of the ends being removable and provided with a key-slot and a portion adapted to form locking engagement with the receptacle, a key con-

trolling ward carried by said removable end adjacent to the key-slot, means secured to the removable end whereby the coins will be held out of contact with said locking portion, and means whereby removal of the coins through the coin-slot is prevented.

5. In a coin savings bank comprising an elongated receptacle with the distance between the front and rear walls thereof being less than the diameter of the coin for which the receptacle is intended, a removable end for the receptacle provided with a key-receiving opening and a flange adapted to telescope into the receptacle, a portion of said flange being partially severed circumferentially to provide a yielding detent or locking tongue, and a key engaging lip carried by said tongue for flexing the tongue out of latching position.

6. In a coin savings bank of the character described, a removable end provided with a flange of resilient metal adapted to enter the end of the receptacle, a portion of said flange having a pair of circumferentially disposed slits joined at one end by a transverse slit to provide a flexible tongue, the severed end being provided with a latch member receiving aperture, or socket, said tongue intermediate of said aperture and the connected end being further partially severed and off-set inwardly and in a direction lengthwise of the main tongue to provide a key engaging portion whereby the free end of the tongue with its aperture may be flexed out of latch engaging position.

7. A coin bank composed of a single blank bent into a tubular receptacle oblong in cross section so that the distance between the front and rear walls is less than the diameter of the coin, one end of the tubular receptacle being immovably secured in place in a sloping manner, while the other end is removably secured and is provided with a flexible latch portion, a coin slot in said removable end, a transversely disposed depending flange on the inner surface of said removable end intermediate of the coin slot and said flexible latch portion, and a spring clip integral with said removable end and disposed in a direction lengthwise of the receptacle.

JAMES M. BUTCHER.
